UNITED STATES PATENT OFFICE.

JOHN M. GRIEST, OF CHICAGO, ILLINOIS, ASSIGNOR TO THE SINGER MANUFACTURING COMPANY OF NEW JERSEY.

GUIDE FOR SEWING-MACHINES.

SPECIFICATION forming part of Letters Patent No. 394,970, dated December 25, 1888.

Application filed December 27, 1887. Serial No. 259,095. (No model.)

To all whom it may concern:

Be it known that I, JOHN M. GRIEST, a citizen of the United States, residing at Chicago, in the county of Cook and State of Illinois, 5 have invented certain new and useful Improvements in Quilting-Guides for Sewing-Machines, of which the following is a specification, reference being had therein to the accompanying drawings.

10 The object of my invention is to provide a convenient "quilter" or quilter-guide for sewing-machines, adapted to be readily secured in operative position or removed from the machine, and also adapted to be used as a 15 quilting-guide or as an ordinary edge-guide.

To this end I provide a bracket or support (which is adapted to be secured to an attachment-holding bar) with a notched or forked portion to embrace a tenon on said bar. The 20 said bracket is also provided with ears, through which is passed the guide-carrying bar, and between the said ears is arranged a clamping device to secure the said guide-carrying bar in any position to which it may be adjusted. 25 The guide has square corners on one side and rounded corners on the other, and is pivoted on its holding or carrying bar, so that it may be turned either side downward. When it is to be used as a quilting-guide, the side with 30 the rounded corners is turned downward, so that the work passing beneath same will not catch thereon; but when it is to be used as an edge-guide the side with square corners is turned downward, so that the edges of the 35 fabric to be guided cannot get under it.

In the drawings, Figure 1 is a perspective view of one form of my improved device with the guide arranged for quilting, and Fig. 2 is a sectional view of the same through 40 the clamping-screw and showing the guide arranged for use as an edge-guide. Figs. 3 and 4 are views similar to Figs. 1 and 2, illustrating another form of my invention; and Figs. 5 and 6 are like views illustrating still 45 another modification.

A denotes the bracket or support, having a forked portion, *a*, by which it may be attached to an attachment-holding bar, and having also 50 perforated ears *a'*, through which passes the bar B, the latter being bent around to form a return-arm, *b*, to the end of which the guide

C is somewhat loosely riveted, so that it may be turned either side up, the said arm thus serving as a pivotal support for the said guide, and the corners of the latter being 55 square on one side or edge and rounded on the other.

In the forms of my invention shown in Figs. 1, 2, 3, and 4 the guide-carrying rod or bar B is held in place in the bracket A by a 60 clamping device consisting of a screw, *d*, placed between the ears *a'* and having a perforated head or loop, *d'*, through which the said rod or bar passes, the said screw being furnished with a set-nut, *e*, which may be 65 tightened to draw the said head or loop firmly against the said rod and hold the latter in place. In the form of my invention shown in Figs. 1 and 2 the set-nut impinges against a cap or housing plate, *f*, which, in connection 70 with the ears *a'*, completely incloses the loop or head of the screw and forms a neat finish to the bracket, the end of the head or loop entering a slot in the front of the bracket to hold the screw from turning or from lateral 75 displacement when the rod is adjusted. In the form of my invention shown in Figs. 3 and 4 the set-nut bears against the back of the bracket.

In the form of my invention shown in Figs. 80 5 and 6 the screw *d* is riveted into the front of the bracket, and the latter has between the ears *a'* an upturned portion, *a''*, against which the set-nut *f* impinges, and which, when the said nut is tightened, is forced against the 85 rod B, to secure the latter in place. In all of these forms of my invention the rods or bars B will be free to be adjusted through the ears of the brackets, to bring the guide C nearer to or farther from the needle when the set- 90 nuts are loosened, but will be held securely in place when the said set-nuts are tightened, as will be obvious.

When the device is to be used as a quilter or quilting-guide, the guide proper, C, is 95 turned so that its rounded corners will be downward, as shown in Figs. 1, 3, and 5, so that the work passing beneath said guide will not catch thereon; but when it is desired to employ the said guide C as an edge-guide it 100 will be turned so that its square corners are down, as in Figs. 2, 4, and 6, and when in this

position it will be adjusted close to the work-plate of the machine, and the square corners will prevent the edges of the fabrics to be guided from getting under the said guide.

5 I claim—

1. A quilting-guide for sewing-machines, consisting of the combination of the supporting-bracket A, having the notched or forked portion *a* and the perforated ears *a'*, the rod 10 B, passing freely through said ears and provided with the return-arm *b*, a clamping part which is supported by said bracket, and which impinges against said rod between said ears, a screw and set-nut for tightening said 15 clamping part against said rod to secure the latter in any position to which it may be adjusted, and a guide at the end of said arm.
2. A quilting guide or gage for sewing-machines, consisting of the bracket A, having the 20 notched or forked portion *a* and the perforated ears *a'*, the rod B, passing freely through said ears and provided with the arm *b*, a

clamping part impinging against said rod between said ears, a screw and set-nut for tightening said clamping part against said rod to 25 secure the latter in any position to which it may be adjusted, and a guide pivotally attached to said arm *b* and provided with square corners on one side and rounded corners on the other side.

30

3. The combination, with the supporting-bracket having the perforated ears, of the rod passing through said ears, a guide carried by said rod, a screw having a perforated head or loop arranged between said ears and surrounding said rod, a set-nut on the said screw, and a cap or housing plate against which said nut impinges.

35

In testimony whereof I affix my signature in presence of two witnesses.

JOHN M. GRIEST.
